E. B. ARMS

POCKET CASE

Filed April 18, 1922

Inventor:
Edward B. Arms,
by J. H. McCrady
his Atty.

UNITED STATES PATENT OFFICE.

EDWARD B. ARMS, OF SOUTH DEERFIELD, MASSACHUSETTS, ASSIGNOR TO ARMS MANUFACTURING COMPANY, OF SOUTH DEERFIELD, MASSACHUSETTS, A VOLUNTARY ASSOCIATION OF MASSACHUSETTS.

POCKET CASE.

Application filed April 18, 1923. Serial No. 555,458.

To all whom it may concern:

Be it known that I, EDWARD B. ARMS, a citizen of the United States, residing at South Deerfield, in the county of Franklin and State of Massachusetts, have invented certain new and useful Improvements in Pocket Cases, of which the following is a specification.

This invention relates to wallets, pocket cases and the like designed to hold money, papers, passes, cards, etc. It is the chief object of the invention to devise a case of this general character which will have provision for holding, in a convenient form for display, a number of passes, photographs, samples, or the like, and which can be folded into a compact form suitable for the pocket.

The nature of the invention will be readily understood from the following description when read in connection with the accompanying drawings, and the novel features will be particularly pointed out in the appended claims.

In the drawings,

Figure 1 is a perspective view of a case constructed in accordance with the present invention;

Fig. 2 is a cross sectional view on the line 2-2, Fig. 1;

Fig. 3 is a cross sectional view through the case when partially folded; and

Fig. 4 is a plan view of the case when closed.

The construction shown consists of a substantially rectangular piece of leather, or other suitable material, which forms the body of the case and may be considered as consisting of a central rectangular cover 2 provided with flaps 3 and 4 extending laterally from opposite sides thereof. This cover is of substantially rectangular form and has a tab 5 extending from one of its ends.

The case shown is designed especially for holding passes, identification cards, photographs, samples and the like, and consequently it is provided with a great number of pockets having transparent walls or windows. Two of these windows 6 and 7, respectively, are provided on the inner surface of the cover 2, each window consisting of a sheet of celluloid secured in a binding 8 of leather, tape, or the like, which is stitched to the cover on three sides, leaving one side of the pocket, in this case that at the right,

Figs. 1 and 2, open for the introduction of 55 the card, photograph, sample, or other article.

Each of the flaps 3 and 4 is provided with four windows, two on each side, those on the inner surface of the flap 3 being designated 60 at 10 and 11, respectively, and those on the corresponding faces of the flap 4 at 12 and 13. These windows are made in the same general manner as the windows 6 and 7, their unsecured edges preferably being 65 toward the cover 2, as best shown in Fig. 4. The windows in the outer face of the two flaps 3 and 4 are formed by cutting out rectangular pieces of the flap to provide suitable openings, and then closing these openings with sheets of celluloid. The celluloid sheets forming the windows opposite the windows 11 and 13 are shown in Fig. 2 at 15 and 16, respectively. In this construction two pockets are thus provided in each flap, 70 and the opposite walls of each pocket are transparent, or, in other words, consist of the windows above described. It will be observed that the outer edges of the windows 15 and 16 are secured under the edges 17 of 75 the sheet of material which forms the main body of the case, these edges 17 being turned over and stitched, as clearly shown in Figs. 1 and 2. The inner edges of the windows 15 and 16 are placed under the edges of the 80 sheet 18 of lining material and are sewed both to the body of the case and to the lining. If the main body of the case does not require a lining, as for instance when it is made of pigskin, then the inside edges of 85 the outer windows on the flaps may be secured to the body by binding and stitching them thereto, in the same manner that the left-hand edge, Fig. 2, of the window 7 is secured to the part 2.

The case is shown in Figs. 1 and 2 in its open condition. In order to close it, the flaps 3 and 4 are first folded inwardly, one on the other and both overlying the cover 2, as shown in Fig. 3. Both the flaps and the cover are then folded on a transverse line lying between, and parallel to, the adjacent edges of the windows 6 and 7. In this condition the cover 2 encloses all the other parts of the case. The tab 5 is then 100 folded over the upper end of the case and is fastened in this position by means of a snap fastener, one part 19 of which is se-

2
cured in the tab, while the other part 20 is secured in the proper position on the cover 2.

In order to facilitate the folding of the case in the manner described, holes 21 and 22 are formed therein at the intersections of the lines on which the case is folded. This avoids the bunching of the material which otherwise would occur at these points. 10 The holes preferably are semi-circular in form so that the end of the folded case is square, as shown in Fig. 4.

It will now be seen that this construction provides a very convenient case which can 15 be folded into a compact form of suitable size to be carried in the vest pocket. In the construction illustrated six pockets and ten windows are provided, but for many purposes a smaller number is ample and in 20 some cases, therefore, only one of the flaps 3 or 4 is provided. It is also contemplated that some of the windows may be omitted if desired. It will be appreciated that the 25 illustrated embodiment of the invention may be modified in other particulars without departing from the spirit or scope of the invention.

Having thus described my invention, what I desire to claim as new is:

30 1. A case of the character described, comprising a cover of approximately rectangular form with a tab extending from one end thereof, a flap of substantially the size of the cover extending laterally from one side of

said cover and adapted to be folded inward- 35 ly upon the cover, said cover and flap there- after being foldable on a line transverse to the first line of fold to enable the cover to enclose the flap, said flap having two windows in each side thereof, with pockets be- 40 tween said windows, and said cover having two windows on its inner surface, the cover having an opening therein at the intersection of said lines of fold to facilitate the folding of the device, and cooperating fas- 45 tenings carried by said tab and cover for securing the cover in its folded condition.

2. A case of the character described, comprising a cover of approximately rectangular form with a tab extending from one end 50 thereof, a flap of substantially the size of the cover extending laterally from each side of said cover and adapted to be folded inwardly one upon the other and both super- posed upon the cover, said cover and flaps 55 thereafter being foldable on a line trans- verse to the first lines of fold to enable the cover to enclose both flaps, each of said flaps having two windows in each side there- of with pockets between said windows and 60 said cover having two windows on its inner surface, the cover having openings therein at the intersections of said lines of fold to facilitate the folding of the device, and co- 65 operating fastenings carried by said tab and cover for securing the cover in its fold- ed condition.

EDWARD B. ARMS.
